[57] CLAIM

The ornamental design for a bottle, as shown and described.

DESCRIPTION

FIG. 1 is a front elevation of a bottle showing our new design;

FIG. 2 is a top plan view thereof;

FIG. 3 is a bottom plan view thereof;

FIG. 4 is a left side elevation thereof; and,

FIG. 5 is a right side elevation thereof.

The rear elevation not shown is a mirror image of the front elevation shown in FIG. 1.
